(57) **CLAIM**

The ornamental design for a cutting tool, as shown and described.

DESCRIPTION

FIG. 1 is a front view of a cutting tool of a first embodiment showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a perspective view thereof;

FIG. 8 is a cross sectional view taken along line 8-8 in FIG. 1;

FIG. 9 is a cross sectional view taken along line 9-9 in FIG. 1;

FIG. 10 is an enlarged view of the portion 10 in FIG. 8;

FIG. 11 is an enlarged view of the portion 11 in FIG. 9;

FIG. 12 is a referential view showing the state in use thereof;

FIG. 13 is a front view of a cutting tool of a second embodiment showing our new design;

FIG. 14 is a rear view thereof;

FIG. 15 is a right side view thereof;

FIG. 16 is a left side view thereof;

FIG. 17 is a top view thereof;

FIG. 18 is a bottom view thereof;

FIG. 19 is a perspective view thereof;

FIG. 20 is a cross sectional view taken along line 20-20 in FIG. 13;

FIG. 21 is a cross sectional view taken along line 21-21 in FIG. 13;

FIG. 22 is an enlarged view of the portion 22 in FIG. 20;

FIG. 23 is an enlarged view of the portion 23 in FIG. 21; and,

FIG. 24 is a referential view showing the state in use thereof. The broken lines shown in views represent portions that form no part of the claimed design.
